UNITED STATES PATENT OFFICE.

WILLIAM S. MACLEWEE, OF YARDLEY, PENNSYLVANIA, ASSIGNOR TO CARRIE HOWELL
MACLEWEE, OF YARDLEY, PENNSYLVANIA.

FUSE-PLUG.

1,243,850.

Specification of Letters Patent. Patented Oct. 23, 1917.

Application filed November 23, 1915. Serial No. 63,042.

To all whom it may concern:

Be it known that I, WILLIAM S. MACLEWEE, a citizen of the United States, residing at Yardley, in the county of Bucks and 5 State of Pennsylvania, have invented certain new and useful Improvements in Fuse-Plugs, of which the following is a specification.

My invention relates to improvements in 10 a fuse plug and the object of my invention is to construct a fuse plug with a porcelain body portion and a metal cap, which latter is protected by the projecting flange formed at the top of the body portion; a further 15 object of my invention is to provide novel means for securing the metal cap upon the body portion and a still further object of my invention is to construct the body portion so that a metal shell carrying the fuse 20 wire may be readily secured thereto.

Referring to the accompanying drawing in which like references refer to like parts; Figure 1 is a perspective view of my improved fuse plug; Fig. 2 is a vertical section 25 of the fuse plug; Fig. 3 is a sectional perspective view of the porcelain body portion; Fig. 4 is a perspective view, partially in section, of the metal cap, detached; and Fig. 5 is an inverted section on line 5—5, 30 Fig. 2.

In the drawings 1 represents the body portion which is made of porcelain or other insulating material. The body portion 1, is provided with an enlarged flange 2, at 35 the top thereof. The central part of the body portion is hollow—forming a chamber with a cylindrical opening at the top and a cylindrical opening, somewhat reduced in size, at the bottom of the body portion.

40 The body portion has an annular groove 4, formed in the top surface thereof, which groove is larger in diameter than the central opening in the body portion, thus leaving a wall 5, over which fits the metal cap 6.

45 As shown in Figs. 3 and 5, oppositely disposed openings 8 and 9 are formed through the flange 2, which openings 8 and 9 communicate with the bottom of the groove 4 formed in the top surface of the flange.

50 The cylindrical flange 10 of the metal cap 6, is provided with arms 12 and 13, which are adapted to be inserted through the openings 8 and 9 in the body portion 1, and the arms are bent outwardly to hold the metal cap 6 55 in place. The under side of the flange 2,

of the body portion has recesses 15 and 16 formed therein to receive the ends of the arms 12 and 13, after they have been bent outwardly which allows them to be protected by the flange 2 and also to better hold the 60 cement or paste 17, which is used to cover the ends of the arms 12 and 13.

The top end of the fuse plug is closed by a transparent disk 20 which also makes the 65 interior of the body portion visible through the aperture formed in the metal cap 6.

Upon the upper surface of the wall 5, of the body portion are formed ribs 21, to hold the transparent disk 20 a sufficient distance 70 from the body portion to permit the escape of gases when the fuse wire is melted. As the cylindrical flange 10 of the cap 6 fits loosely over the wall of the body portion there is ample ventilating space formed 75 around the metal cap.

A metal shell 25 having a screw thread formed thereon is secured upon the lower end of the body portion by forcing portions of the upper edge of the metal shell into the recesses 26 and 27 formed in the body 80 portion.

The body portion is provided with a vertical slot 28, to receive the contact plate 30 carried by the shell 25 which allows the shell to be placed upon the lower end of 85 the body portion. An insulating disk 31 is held between the lower end of the body portion and the flange 32 of the shell 25 and said disk 31 carries a contact button 33 to which is attached one end of the fuse wire 90 35, having its other end attached to the contact arm 30 of the metal sleeve 25.

Having thus described my invention, I claim and desire to secure by Letters Patent:

1. A fuse plug comprising a body portion having a central chamber, said body portion having a groove formed in the top surface thereof, a transparent disk covering said chamber, a metal cap to hold the transparent disk, an enlarged flange formed upon the body portion, arms formed upon the metal cap adapted to project through openings in the body portion and to be secured below the projecting flange of the body portion. 100

2. A fuse plug comprising a body portion having a central chamber, said body portion having an annular groove formed in the top surface thereof, a metal cap having a cylindrical flange adapted to enter said groove 110

- formed in the body portion, arms upon the metal cap, openings formed in the body portion extending from the bottom of the said groove to receive the arms of the metal cap,
5 an enlarged flange formed upon the body portion, and said flange having recesses formed in the under side thereof to receive the ends of the arms of the metal cap.
3. A fuse plug comprising a body portion
10 having a central chamber, said body portion having an annular groove formed in the top surface thereof forming a circular wall around the outlet of the said chamber, ribs formed upon the top surface of the said

wall, a transparent disk, a metal cap to hold 15 the said disk upon the ribs of the wall, a circular flange upon the metal cap fitting loosely over the said wall, an enlarged flange formed upon the body portion to surround the metal cap, and means for securing the 20 flange of the metal cap to the body portion.

In testimony whereof I have affixed my signature in presence of two witnesses.

WILLIAM S. MacLEWEE.

Witnesses:

ROBERT M. WALLACE,
EARL D. SHAFFER.
